UNITED STATES PATENT OFFICE.

FRANK A. HALE, OF CHICAGO, ILLINOIS.

STAND FOR MEMORANDUM-CALENDARS.

1,179,093.

Specification of Letters Patent. Patented Apr. 11, 1916.

Application filed October 16, 1915. Serial No. 56,256. *To all whom it may concern:*

Be it known that I, FRANK A. HALE, a citizen of the United States, and resident of Chicago, county of Cook, and State of Illinois, have invented certain new and useful Improvements in Stands for Memorandum-Calendars, of which the following is a specification, and which are illustrated in the accompanying drawing, forming a part thereof.

The invention relates to calendars, and more particularly to those comprising a pad of separate leaves and a holder therefor providing means for filing the leaves of the pad in two positions and for guiding the leaves while being transferred from one position to the other.

The object of the invention is to provide a stand or holder for calendars of the type described, which shall be of simple and inexpensive construction, with provision for the convenient separation and assembling of its parts for the removal and replacement of the calendar pad.

In the accompanying drawings,—Figure 1 is a perspective view, partly broken away, showing a stand for memorandum calendars embodying the features of improvement provided by the invention; Fig. 2 shows one of the filing arches of the stand separated from other parts; Fig. 3 is a detail end view of the stand, having a part broken away, and Fig. 4 is a perspective view showing a form of locking plate which may be employed for securing the filing arches to the base of the stand.

In carrying out the invention a base 10, preferably constructed from a sheet metal plate 11 of sufficient size to provide two seats for the leaves of the calendar pad, not shown, is employed. The filing arches, as 12 and 13, are of spring metal, as wire, and of U-shape. In the particular form of construction illustrated in the drawings, these arches are of different size, and they are arranged in a common plane.

In constructing the base 10 the greater portion of the sheet metal plate 11 remains flat, but a portion 14 of the plate extending along its rear edge is bent downwardly and then folded inwardly and upwardly to provide an upwardly facing groove 15 below the body of the plate in line with the arches, as 12 and 13. The walls of the groove 15 further serve as a supporting leg for maintain-

ing the body portion of the plate 11 in a suitably inclined position.

The arches 12 and 13 are supported by passing their ends downwardly through openings, as 16, in the plate 11, and into the groove 15. Preferably the sides of the arches, as 12, are made somewhat flaring, as indicated by full lines in Fig. 2, whereby they must be elastically compressed to the form indicated by dotted lines in Fig. 2, before their ends can be inserted in the corresponding openings 16 in the plate 11. Furthermore, the arches, as 12, are desirably notched upon the outside adjacent each end, as at 17 (Fig. 2) for engagement with the margins of the openings 16, when the extreme lower ends of the arches have been entered in the groove 15.

The invention provides a construction which may be very inexpensively made and from but a few parts. The form of the arches 12 and 13, and the engagement of the notches 17 with the margins of the openings 16, renders the arches rigid against displacement in any direction in their own plane. Displacement of the arches in directions transverse to their plane is effectively prevented by the seating of the ends of the arches in the groove 15. On the other hand, whenever there is occasion for removal of the arches this is readily accomplished by compressing them to disengage the notches 17 from the margins of the openings 16.

A finished appearance is provided if downturned flanges, as 20, are formed at the ends of the plate 11 and the forward edge of the plate is overturned to provide a roll or bead 21. Under these circumstances the flanges 20 preferably terminate a short distance above the level of the lowest parts of the downturned portion 14 and bead 21, whereby their edges are held out of contact with the desk or table (not shown) upon which the article is to be supported, and the scratching or marring of a finished surface is avoided.

In some instances it may be desirable to provide a locking device for preventing the compression of the sides of the arches 12, 13 when the notches 17 are engaged with the margins of the openings 16. Accidental displacement of the arches is thus positively prevented. As shown, a locking plate generally designated 22 is employed. This locking plate is located within the base 10 be-

tween the under side of the main body portion of the plate 11 and the upturned free edge of the folded portion 14. The simplest form of construction is provided if the 5 locking plate 22 is made to swing upon one of the sides of the arch 13, as a pivot. To this end the locking plate 22 is provided with an aperture 23 near one end in order that one of the sides of the arch 13 may pass 10 through it. The locking plate is also provided with lateral projections 24 and 25, one for engaging the other side of the arch 13 upon the inside and the other for entering the space between the two sides of the 15 arch 12. The projection 24 is provided with a rounded nose 26, which is required to be forced by the said other side of the arch 13 in swinging the locking plate between its open and closed positions.

20 I claim as my invention,—

1. A holder for pad calendars comprising, in combination, a sheet metal base plate having a row of apertures extending along the same adjacent one edge, that part of the 25 plate beyond the row of apertures being folded downwardly and then inwardly and upwardly to provide an upwardly facing groove below the body of the plate in line with the row of apertures, and a pair of filing arches of unequal span each having both its ends extended through apertures of the plate and seated in the said groove.

2. A holder for pad calendars comprising, in combination, a sheet metal base plate having a row of apertures extending along the same adjacent one edge, that part of the 35 plate beyond the row of apertures being folded downwardly and then inwardly and upwardly to provide an upwardly facing groove below the body of the plate in line with the row of apertures, and a pair of elastic filing arches of unequal span each arch being notched upon the outside adj-

cent both its ends and both ends of each arch being extended through apertures of 45 the plate and seated in the said groove, each notch being engaged with the plate at the margin of the corresponding aperture.

3. In a holder for pad calendars, in combination, a sheet metal base plate having a 50 pair of apertures arranged in a line parallel to and adjacent one edge of the plate, that part of the plate beyond the apertures being folded downwardly and then inwardly and upwardly to provide an upwardly facing 55 groove below the plate in line with its apertures, and a filing wire elastically bent to form an arch equal in width to the spacing of the apertures and notched upon the outside of the arch adjacent both ends, the ends 60 of the wire being passed through the apertures of the plate and seated in the said groove, and its two notches being each engaged with the plate at the outer margin of the corresponding aperture.

4. In a holder for pad calendars, in combination, a sheet metal base plate having a pair of apertures arranged in a line parallel to and adjacent one edge of the plate, that part of the plate beyond the apertures being folded downwardly and then inwardly and upwardly to provide an upwardly facing groove below the plate in line with its apertures, a filing wire elastically bent to form an arch equal in width to the spacing of the 75 apertures and notched upon the outside of the arch adjacent both ends, the ends of the wire being passed through the apertures of the plate and seated in the said groove, its two notches being each engaged with the 80 plate at the outer margin of the corresponding aperture and a locking plate swingingly mounted upon one side of the arch and forcibly engaging the other side of the arch upon the inside.

FRANK A. HALE.
